ATTORNEY

UNITED STATES PATENT OFFICE.

LYMAN C. WOOD, OF WICHITA, KANSAS.

VEHICLE-SPRING.

SPECIFICATION forming part of Letters Patent No. 269,149, dated December 12, 1882.

Application filed May 18, 1882. (No model.)

To all whom it may concern:

Be it known that I, L. C. WOOD, a citizen of the United States, residing at Wichita, in the county of Sedgwick and State of Kansas, have invented certain new and useful Improvements in Vehicle-Springs, of which the following is a specification, reference being had therein to the accompanying drawings, and in which—

Figure 1 is an end view of my improved vehicle-spring. Fig. 2 is a side view thereof, and Fig. 3 is a detailed view of the same.

This invention has relation to an improvement in light vehicles, more particularly to the springs, specially designed for riding, though adapted for carrying purposes, its object being to avoid sudden reaction, which would cause breakage of the springs, and to effect the adjustment of the vehicle-body to a high or low position without impairing the motion of the spring or its capacity; and it consists in the detailed construction of the spring, and the manner of its attachment to the body and of supporting the body thereon, substantially as hereinafter more fully set forth and claimed.

In carrying out my invention I employ or make a spring composed of two sections or halves, A A, each a spring in itself. Each half or section A is formed with an inclined or oblique portion, a, having a straight or horizontal arm, a', at one end and an upwardly-curved portion, a², at its other or lower end. The two sections or halves A A are arranged with the upper ends of their oblique portions touching each other, and secured together thereat, so as to have the required play, as shown, preferably by plates B. These plates have flanges b, one set of each plate being secured to each section of the spring. These plates have also each an upwardly-projecting portion or flange, b'.

C is the vehicle-body, having bolted to its under side at each end a plate, c, from the middle of which depends an apertured projection, c'. The flanges b' of the plate B of the spring-sections are bolted to the projection c', thus effecting the attachment of the spring or

springs to the vehicle-body. The ends of the horizontal portions or arms a' of the spring-sections are connected by bolts d, fitted with springs d', to opposite sides of the vehicle-body at its ends. The arms a' of the spring-sections A are free to move upon the bolts d, and are acted upon by the springs d', through which the weight of the vehicle-body is received upon the said arms. This arrangement distributes the weight upon the springs, avoids sudden reaction, which would cause the breakage of the springs, and permits the adjustment of the vehicle-body to a high or low position. The upwardly-curved ends of the spring-sections A A are clipped or bolted to the ends of the side spring-bars, D, suitably secured to the running-gear.

I claim and desire to secure by Letters Patent—

1. In a vehicle-spring, the combination, with the spring-sections A, having upwardly-extending portions a² at their outer ends, the oblique portions a, and the horizontal portions a', of the plate c, secured to the vehicle-body and having a perforated projection, c', and the plate B, having the flanges b and the upwardly-projecting flanges b', substantially as and for the purpose set forth.

2. In a vehicle-spring, the combination, with the spring-sections A, having the oblique portions a, provided with the horizontal arms a' and upwardly-curved portions a², connected to the spring side bars secured to the running-gear, of the plates B, having flanges b and upwardly-projecting flanges b', plate c, having a depending projection, c', and the bolts d, fitted with springs d' and depending from the vehicle-body, substantially as and for the purpose set forth.

In testimony whereof I affix my signature in presence of two witnesses.

LYMAN C. WOOD.
